WALL SWITCH

Robert I. Innis, Winthrop, Mass.

Application January 3, 1938, Serial No. 183,081

15 Claims. (Cl. 200—168)

My invention relates to wall switches such as are installed in homes, offices and other places for controlling electric lighting circuits and the like, and to ornamental cover attachments for existing switches of that class.

The invention has for its object to improve the construction and appearance of electric switches of the class described.

To this end I provide a switch of the class described having a supplemental cover member, preferably ornamental, forming an exterior part thereof which is supported close to the outer surface of the wall and which incloses the usual operating mechanism, said cover member having associated therewith auxiliary means operable through movement imparted thereto manually to operate the switch.

The cover member is preferably provided as an attachment for existing switches and may be either fixedly or movably supported thereby.

In the accompanying drawings:

Figure 1 is a front elevation of a wall switch mechanism constructed in accordance with my invention.

Figure 2 is a section on line 2—2 of Fig. 1.

Figure 3 is a view similar to Fig. 1 but with the cover member removed.

Figure 4 is a section on line 4—4 of Fig. 2.

Figure 5 is a vertical sectional view illustrating a second form of the invention.

Figure 6 is a section on line 6—6 of Fig. 5.

Figure 7 is a central vertical sectional view of a third form of switch mechanism constructed in accordance with this invention.

Figure 8 is a front view of the mechanism shown in Fig. 7 but with the cover member removed.

Figure 9 is a section on line 9—9 of Fig. 7.

Figure 10 is a rear elevation of the cover member shown in Fig. 7.

Figure 11 is a vertical sectional view illustrating a fourth form of this invention.

Figure 12 is a central vertical sectional view of a fifth form of switch mechanism constructed in accordance with this invention.

Figure 13 is a front elevation of the mechanism shown in Fig. 12 but with the cover member removed.

Figure 14 is a section on line 14—14 of Fig. 12.

Figure 15 is an elevation of the lower end of the mechanism shown in Figs. 12 and 16.

Figure 16 is a central vertical sectional view illustrating a sixth form of the invention.

Figure 17 is a central vertical sectional view of a seventh form of the invention.

Figure 18 is a rear elevation of the cover member of the mechanism shown in Fig. 17.

A common form of wall switch comprises a porcelain body 10 fastened to a metal bridge bar 12 which in turn is fastened at its opposite ends

to a switch box 13 by screws 18, said box being incorporated within the wall 14 of the room. The body 10 contains the make-and-break mechanism, not shown, which is operated sometimes by push buttons 15, 15, Figs. 2, 3, 7, 8, 12, 13 5 and 17, and sometimes by a lever 16, Figs. 5, 11 and 16. Two screws 11 secure a face plate 17 to the bridge bar 12, the marginal portion of said plate overlying the part of the wall adjacent to box 13. In the case of the push-button 10 switches the face plate 17 is made near its middle with two holes or apertures as shown in Fig. 7, through which the push-buttons 15 project to the exterior where they were heretofore accessible for direct manual operation, while in the case of the lever switches the face plate 17 was made with a single aperture as shown in Fig. 5 through which the lever 16 projected to the exterior where it was heretofore accessible for direct manual operation. 20

The face plate 17 with the push-buttons 15 or the lever 16 projecting outwardly therefrom was not an ornamental feature of the room within which the switch was arranged and one of the chief objects of this invention is to provide an ornamental cover for these devices which will add to the attractiveness of the room. 25

The embodiment of my invention illustrated in Figs. 1 to 4, inclusive, comprises a rocker-supporting bar or member 19 which is secured in position against the outside of the face plate 17 by the original screws 11, 11 after said plate has been removed and replaced in reversed position as shown, it being understood that ordinarily the face plate is disposed relatively to the wall as shown in Fig. 7. 30

The bar 19 is made with a central rectangular aperture 20 adjacent to the middle of which are two outstanding ears 21, one at each side of 40 aperture 20, between which is arranged a rocker 22 having oppositely disposed arms each co-operatively associated with the outer end of one of the push-buttons 15. This rocker 22 is pivotally connected with the ears or lugs 21 by a 45 pintle 23 and near its outer end is formed with apertures which are loosely occupied by the intermediate portion of a wire bail 24 whose legs have their end portions firmly embedded within a handle or fingerpiece 25 whereof the upper 50 portion is slidably mounted within a groove 26 formed upon the inner side of a supplemental cover member 27. The bail 24 and rocker 22 also occupy this groove while the push-buttons 15 are free to move back and forth into and out of 55 the same.

Upon its inner side the cover member 27 is formed with a recess 28 to receive within it the face plate 17. This recess 28 is open at its bottom but at its top and opposite sides is bor- 60

dered by walls 29 and 29', respectively, the inner sides of said walls being beveled as shown so that the opposite side walls 29' provide a vertical or longitudinal dovetail groove. The walls 29 and 29' provide the hollow cover member or attachment 27 with a skirt which extends around the face place with its chime closely adjacent to the wall 14.

After securing the rocker-supporting member 19 and the reversed face plate 17 in position by means of the original screws 11, the cover member 27 is first placed against the wall 14 above the switch mechanism with its open end lowermost and then is slid downwardly so that face plate 17 slidly enters the recess 28, Fig. 4, with its outwardly flaring flanges fitting against the opposite beveled side walls of the dovetail groove provided by the side walls 29' of the cover member 27. Downward movement of the cover member is arrested by the engagement of its top wall 29 with the beveled top portion of the face plate 17. The switch mechanism is now in condition for use and is operated by manually moving the fingerpiece up and down relatively to cover member 27 and face plate 17 in a direction parallel with wall 14.

The cover member 27 is preferably a molded product designed, as shown in Fig. 1, for ornamental effects, particularly upon its exterior, and so as to cover and hide from view all of the original switch mechanism and all of the switch operating mechanism except the fingerpiece 25. This fingerpiece is also preferably a molded product. Suitable materials for use in producing molded parts 25 and 27 are "Bakelite," hard rubber, glass, metal, etc., but said parts may, of course, be produced otherwise than by molding and from other materials.

In Figs. 5 and 6 of the drawings the bridge member 19a is made with a slot 30 that is occupied by the switch lever 16 while the fingerpiece 25 is made with a metal extension slidably held in position against said bridge member by ears 31 provided at the opposite sides of the latter. The extension is made with an aperture 32 through which lever 16 extends and as will be clear the opposite ends of this aperture provide abutments by which the lever 16 is operated by back and forth movement of the fingerpiece and extension.

In Figs. 7, 8, 9 and 10 the face plate 17 is applied to the wall in its usual un-reversed position and the cover member 27a is held in position by flanges 33, one at each side of a supplemental plate member 19b on which the rocker 22 is pivotally mounted. The flanges 33 are disposed vertically and overlie flanges 34 provided upon the inner side of the cover member 27a so that said cover member can be placed in position and removed by sliding the same vertically as will be clear, the upper end of the face plate serving as a stop to limit the downward movement of the cover member as in Fig. 2. Also, in this form of my invention the plate member 19b is made at one end with an outstanding apertured extension 35 through which extend loosely the legs of the bail 24 so that the latter is guided thereby in its up and down movements.

The flanges 33 and 34 provide, in effect, a dovetail tongue and groove connection between the cover member 27a and the supplemental plate member 19b which permits of ready application or removal of the cover member and holds the latter against sidewise displacement.

In Fig. 11 a supplemental plate member 19c is sub-

provided having a single aperture 36 through which the switch operating lever 16 extends into an eye 37 provided at the upper end of a wire stem 38 forming part of the fingerpiece 25. This stem extends loosely through an aperture provided in an outstanding extension 35 of the supplemental plate 19c. Also, in this form of my invention the cover member 27a is held in position by the supplemental plate and the supplemental plate is fastened to the existing switch mechanism by the screws 11 as described in connection with Figs. 7, 8 and 9.

In Figs. 12 to 15, inclusive, the usual screws 11 of the existing switch mechanism are employed, as before, to fasten an apertured supplemental plate 19d in position upon the outer side of the usual face plate 17 and this plate 19d is made with two pairs of flanges 33 overlying complementary flanges 34 on the interior of the cover member 27b which is formed upon its inner side with a cavity or recess for the accommodation of face plate 17 and the push-button operating mechanism.

The push-button operating mechanism referred to includes a rocker member 22a made with oppositely projecting arms to engage the outer ends of the push-buttons 15. This rocker member is pivotally mounted at 23 upon the supplemental plate member 19d and at its outer end is provided with a radial pin or stud 39 occupying an aperture 40 formed at the middle of a longitudinally disposed resilient metal strip 41 fixedly mounted within the cover member 27b.

In this form of my invention the switch is operated by manually sliding the cover member up and down on the face plate 17, the rim or chime of the cover member engaging the upper end of the face plate to limit the downward movement of said member and also engaging the lower end of supplemental plate member 19d to limit the upward movement thereof.

At the lower end of the cover member 27b the rim or skirt thereof is formed with an indenture or passageway 42 through which the face plate 17 and the lower end portion of supplemental plate 19d can pass when the cover member is first shoved downwardly from above to apply it to the existing switch after the latter has been equipped with the supplemental plate member 19d. The lower end portion 43 of supplemental plate 19d serves as a leaf spring and is set in an outwardly bent condition as shown and normally its free end serves as a stop to limit the upward movement of cover member 27b through the engagement of the inner side of the cover skirt opposite the points 44, Fig. 15, with said end.

The parts of the cover skirt which engage the end of the spring portion 43 are at opposite sides of a notch 45 through which a tool may be passed to press down the spring portion 43 when it is desired to remove the cover member 27b upwardly. It will be understood that when the cover member is being applied to the switch by downward movement thereof the portions 44 of the cover pass over and depress the spring stop portion 43 until the portions 44 pass below the same whereupon the spring-stop 43 springs outwardly and remains in position to serve as an up stop.

During the application and during the removal of cover 27b the pin or stud 39 will bend or flex the strip 41 so that the pin is forced into and out of the aperture 40. During the normal operation of the device, however, the pin 39 remains within the aperture 40.

In Fig. 16 a bowed resilient strip 41a is sub-

75.

stituted for the straight strip 41 of Fig. 12 and said strip 41a is made adjacent to its middle with an aperture 40a that is occupied by the switch operating lever 16. Otherwise the construction illustrated in Fig. 16 is approximately the same as that of Fig. 12.

In the form of my invention illustrated in Figs. 17 and 18 a supplemental plate member or element 19e is employed which is made with a central aperture 46 at the opposite sides of which are provided ears or lugs 47 between which a button-operating rocker 22 is pivotally mounted upon a pintle 23. The outer end of rocker 22 has pivotally connected to it a wire bail 24 carrying a fingerpiece 25 at the lower ends of its two legs.

The two plates 19e and 17 are fastened to the switch body 18 by two screws 11a as in the other forms of this invention but, while the original screws 11, not shown, can be utilized, I may employ two screws 11a whose heads project outwardly beyond plate 19e a substantial distance to occupy vertical slots 47 and 48 provided in two sheet metal plates 49 and 50, respectively, fastened in position within the cover member 27c by screws as shown in Fig. 18.

The upper slot 47 opens into a cavity or recess 51 provided upon the interior of the cover member while the lower end of slot 48 is made with an enlargement 52 sufficiently large to serve as a passageway for the head of the lowermost screw 11a. The heads of the screws 11a are of inverted conical shape so as to interlock with the side walls of the slots 47 and 48 thereby to hold the cover member 27c in position on the switch and stationary while the fingerpiece 25 is moved up and down to operate the switch mechanism.

It will be clear that the cover member may be applied to the switch by first placing the same in a position where the lower screw 11a occupies the enlargement 52 and the upper screw occupies the cavity 51 directly beneath slot 47 and then sliding the cover member downwardly until the heads of screws 11a are at the upper ends of the slots 47 and 48. It will be clear that the cover member is as easily removed.

What I claim is:

1. The combination with a wall switch of the character described comprising a body adapted to be fixed within a cavity in the wall; an apertured face plate fastened to said body whose marginal portion overlies the outer face of the wall adjacent to and surrounding said cavity, and switch-operating mechanism projecting from said body through said apertured face plate to the exterior thereof, of an outer hollow supplemental cover attachment inclosing and concealing said face plate and said operating mechanism; means entirely concealed beneath said supplemental cover attachment for securing the latter to said wall switch, and means within said supplemental cover attachment that is manually operable to actuate said switch-operating mechanism.

2. The combination with a wall switch of the character described comprising a body adapted to be fixed within a cavity in the wall, an apertured face plate fastened to said body whose marginal portion overlies the outer face of the wall adjacent to and surrounding said cavity, and switch-operating mechanism projecting from said body through said apertured face plate to the exterior thereof, of a hollow supplemental cover attachment outside of said face plate for inclosing and concealing the latter and said operating mechanism; means entirely concealed beneath

said supplemental cover attachment for separably connecting the latter with said wall switch, and means within said supplemental cover attachment that is manually operable to actuate said switch-operating mechanism.

3. The combination with an existing wall switch of the character described comprising a body adapted to be fixed within a cavity in the wall, an apertured face plate fastened to said body whose marginal portion overlies the outer face of the wall adjacent to and surrounding said cavity, and switch-operating mechanism projecting from said body through said apertured face plate to the exterior thereof, of a hollow supplemental cover attachment outside of said face plate for inclosing and concealing the latter and said operating mechanism, said cover attachment being made with a skirt which extends around said face plate with its chime closely adjacent to said wall; means entirely concealed beneath said supplemental cover by which said cover attachment is connected with said wall switch, and means within said cover attachment that is manually operable to actuate said switch-operating mechanism.

4. The combination with an existing wall switch of the character described comprising a body adapted to be fixed within a cavity in the wall; a beveled apertured face plate fixed reversely to said body whose marginal portion overlies the outer face of the wall adjacent to and surrounding said cavity, and switch operating mechanism projecting from said body through said apertured face plate to the exterior thereof, of a hollow cover upon the outside of said face plate for inclosing and concealing said operating mechanism, said cover being provided upon its inner side with a vertical dovetail groove slidably engaged with the beveled edge of said face plate, and means within said cover that is manually operable to actuate said switch operating mechanism.

5. The combination of claim 4 wherein said cover is provided at its upper end with means engaging the top of said face plate to position said cover vertically relatively to the latter.

6. The combination with an existing wall switch of the character described comprising a body adapted to be fixed within a cavity in the wall, an apertured face plate fixed to said body whose marginal portion overlies the outer face of the wall adjacent to and surrounding said cavity, and switch operating mechanism projecting from said body through said apertured face plate to the exterior thereof, of a hollow cover upon the outside of said face plate for inclosing and concealing said operating mechanism, said cover being provided upon its inner side with a pair of vertical flanges; a member fixed in position upon the outer side of said face plate made with a pair of vertical flanges each slidably engaged with one of the flanges on the cover to hold the latter in position; means for limiting downward sliding movement of the cover relatively to said face plate, and means within said cover that is manually operable to actuate said switch-operating mechanism.

7. The combination with an existing wall switch of the character described comprising a body adapted to be fixed within a cavity of the wall, an apertured face plate fixed to said body whose marginal portion overlies the outer face of the wall adjacent to said cavity, and switch operating mechanism projecting from said body

- through said apertured face plate to the exterior thereof, of a hollow cover upon the outside of said face plate for inclosing and concealing said operating mechanism, said cover being provided upon its inner side with a pair of vertical flanges, a member fixed in position upon the outer side of said face plate made with a pair of vertical flanges each slidably engaged with one of the flanges on the cover to hold the latter in position, 5 a vertically movable actuator for said operating mechanism within said cover and supported by said member, the lower end of said actuator extending below said cover so that it is accessible for manual operation.
- 10 15. 8. The combination with an existing wall switch of the character described comprising a body adapted to be fixed within a cavity of the wall; an apertured face plate whose marginal portion overlies the outer face of the wall adjacent to and surrounding said cavity, screws fastening said face plate to said body, and switch operating mechanism projecting from said body through said apertured face plate to the exterior thereof, of a hollow cover upon the outside of said face plate for inclosing and concealing said face plate, screws and operating mechanism, means concealed between said cover and said face plate through which said cover is supported by said wall switch, and actuating means for said operating mechanism movably mounted within said cover and extending downwardly beyond the same so that it is accessible for manual operation.
- 20 16. 9. The combination with an existing wall switch of the character described comprising a body adapted to be fixed within a cavity of the wall, an apertured face plate fixed to said body whose marginal portion overlies the outer face of the wall adjacent to and surrounding said cavity, screws by which said plate is fastened to said body, and switch operating mechanism projecting from said body through said apertured face plate to the exterior thereof, of a hollow cover upon the outside of said face plate for inclosing and concealing said operating mechanism and screws, a member fixed in position upon the outer side of said face plate by said screws, said member slidably engaging said cover to hold the same in position relatively to said face plate, and means within said cover that is manually operable to actuate said switch-operating mechanism.
- 25 17. 10. The combination with an existing wall switch of the character described comprising a body adapted to be fixed within a cavity of the wall, an apertured face plate fixed to said body whose marginal portion overlies the outer face of the wall adjacent to and surrounding said cavity, screws by which said face plate is fastened to said body, and switch operating mechanism projecting from said body through said apertured face plate to the exterior thereof, of a hollow supplemental cover attachment upon the outside of said face plate for inclosing and concealing said operating mechanism, means entirely concealed from view beneath said supplemental cover attachment for holding the latter in position relatively to said face plate, a member fastened in position upon the outer side of said face plate by said screws, and actuating means for said operating mechanism which is movably supported by said member, said actuating means extend-
- 30 35 40 45 50 55 60 65 70
- ing below said cover so that it is accessible for manual operation.
11. The combination with an existing wall switch of the character described comprising a body adapted to be fixed within a cavity of the wall, an apertured face plate fixed to said body whose marginal portion overlies the outer face of the wall adjacent to and surrounding said cavity, screws by which said face plate is fastened to said body, and switch-operating mechanism projecting from said body through said apertured face plate to the exterior thereof, of a hollow supplemental cover attachment outside of said face plate for inclosing and concealing said face plate, said screws and said operating mechanism, the heads of said screws separably and slidably interlocking with said attachment cover to hold the same in position, and actuating means for said operating mechanism movably mounted within said cover attachment and accessible for manual operation.
- 15 20 25 30 35 40 45 50 55 60 65 70
12. The combination with an existing wall switch of the character described comprising a body adapted to be fixed within a cavity of the wall, an apertured face plate fixed to said body whose marginal portion overlies the outer face of the wall adjacent to and surrounding said cavity, screws by which said face plate is fastened to said body, and switch operating mechanism projecting from said body through said apertured face plate to the exterior thereof, of a hollow supplemental cover attachment upon the outside of said face plate for inclosing and concealing said plate, said operating mechanism and said screws, the heads of said screws separably interlocking with said cover to hold the same in position, and actuating means for said operating mechanism which is movably supported within said cover, said actuating means being accessible for manual operation.
13. A wall switch of the character described comprising a body adapted to be fixed within a cavity in the wall, an apertured face plate fixed to said body whose marginal portion overlies the outer face of the wall adjacent to and surrounding said cavity, switch operating mechanism projecting from said body through said apertured face plate to the exterior thereof, a hollow cover movably mounted upon the outside of said face plate for inclosing and concealing said operating mechanism, and means upon the interior of said cover through which movement of the latter actuates said operating mechanism.
14. A wall switch of the character described constructed in accordance with claim 13 wherein the means upon the interior of the cover through which the operating mechanism is actuated consists of a resilient member by which the operating mechanism is positively actuated.
15. A wall switch of the character described constructed in accordance with claim 13 wherein said cover is slidably and separably connected with said face plate and wherein the means upon the interior thereof through which the operating mechanism is actuated consists of a resilient member that is sprung into interlocking engagement with said operating mechanism when the cover is connected with said face plate.
